[57] CLAIM

The ornamental design for an apheresis system, as shown and described.

DESCRIPTION

FIG. 1 is a perspective view of an apheresis system showing our new design;

FIG. 2 is a front view thereof;

FIG. 3 is a rear view thereof;

FIG. 4 is a side view thereof;

FIG. 5 is a side view thereof, opposite that shown in FIG. 4;

FIG. 6 is a top view thereof; and,

FIG. 7 is a bottom view.

The broken line showing in FIGS. 1-7 is for illustrative purposes only and forms no part of the claimed design.
